ASSEMBLER SLIDE CONTROLLING AND
ACTUATING MECHANISM

George Pankuch, Cleveland Heights, Ohio

Application February 20, 1940, Serial No. 319,884

7 Claims. (Cl. 199—30)

This invention relates to the matrix assembling mechanism of a keyboard controlled type casting machine, and more particularly to the operating mechanism for the assembler slide which serves to hold the line of matrices compactly together as matrices are delivered by the keyboard controlled mechanism to the assembling elevator.

The assembler slides of type casting machines have heretofore been provided with springs of various types for returning them to their initial position upon each actuation of the elevator following the assembly of a line of matrices upon the elevator, a trip operated brake or detent being provided which is operative to prevent rearward movement of the slide until after an assembled line of matrices has been lifted by the elevator to a position clear of the slide. Since there may be considerable variation in the length of the line of matrices assembled on the elevator, and the tension of the return spring must be sufficient to positively return the slide from any position in which it may occupy when the elevator is lifted, it is difficult to provide a spring which will have sufficient tension for insuring return movements of the slide which will not exert too much pressure upon the line of matrices being assembled. Since the feed of matrices is keyboard controlled and the machine operators acquire the ability to operate the keys with great rapidity, it is necessary that the movements of the elevator and slide be quite rapid. Furthermore, if the pressure exerted by the slide upon the line of matrices is not properly regulated, matrices may be thrown out onto the floor by the feed mechanism instead of being delivered into the line of matrices on the elevator.

The present invention has for its object to provide a clutch controlled power operated mechanism for effecting the return movement of the assembler slide, the slide actuating mechanism including a frictional driving connection which serves to limit the force applied to the slide.

A further object of the invention is to provide a slide actuating and controlling mechanism which provides a substantially uniform drag on the slide during the assembly of a line of matrices on the elevator and which provides a substantially uniformly timed return movement of the slide.

With the above and other objects in view, the invention may be said to comprise the assembler slide operating mechanism as illustrated in the accompanying drawing, hereinafter described

and particularly set forth in the appended claims, together with such variations and modifications thereof as will be apparent to one skilled in the art to which the invention pertains.

Reference should be had to the accompanying drawing forming a part of this specification, in which:

Figure 1 is a fragmentary side elevation of the matrix feed mechanism, the elevator, the assembler slide and its actuating mechanism;

Fig. 2 is a top plan view of the slide actuating pulley and its driving means viewed as indicated at 2—2 in Fig. 1;

Fig. 3 is a section taken on the line indicated at 3—3 in Fig. 1;

Fig. 4 is a sectional detail view showing the attachment of the flexible slide operating band to the slip ring on the actuating pulley; and

Fig. 5 is a plan view of the attachment shown in Fig. 4.

In the accompanying drawing the invention is shown applied to a Linotype machine, only those parts of the machine which coact with the assembler slide being shown. A portion of the elevator 1 upon which the lines of matrices are assembled is shown, the elevator 1 having a longitudinally slotted channel 2 which receives the matrices which are delivered to the channel by a delivery belt 3 and a star wheel 4. The delivery belt 3 is continuously driven by a belt 5 and the star wheel 4 is continuously driven by suitable gearing from the delivery belt pulley shaft. A slide bar 6 extends into the elevator channel slot and has a lug 7 against which the first matrix of the line engages and against which the line of matrices in the elevator channel is pressed.

The slide bar 6 is moved forwardly into the elevator 1 by the matrices as they are assembled in the channel 2, and movements of the slide bar 6 are controlled by a brake 8 having shoes 9 and 10 engageable with the top and bottom surfaces of the bar 6. The brake 8 is suspended from a fixed pivot 11 above the bar 6. Swinging movements of the brake 8 cause the shoes 9 and 10 to press against opposite faces of the slide bar so as to resist movements thereof. The brake 8 is normally supported in substantially vertical position, which permits the slide bar 6 to be moved forwardly. The brake 8 may be provided with a lever extension 12 for manual operation. The brake 8 was originally designed to control the movements of the slide by a retracting spring, rearward movement of the brake, causing the

shoes 9 and 10 to clamp the slide bar 6 and prevent rearward movement of the slide. The present invention, however, replaces the slide actuating spring with a power operated actuator and the brake 8 functions differently, as will be hereinafter explained.

A trip operated actuating means is provided for the brake 8 to automatically shift the brake and cause return movement of the slide at the proper time during the cycle of operations.

The trip device includes a bell crank lever 13 mounted on a fixed pivot 14 and having a vertical arm 15 engageable with the rear side of the brake 8 below the pivot 11 and a horizontal 15 forwardly extending arm 16. The arm 16 has an adjustable stop member in the form of a vertical screw 17 which engages the under side of the rearward end of the trip lever 18, the screw 17 being adjustable to properly position 20 the levers 13 and 18. The lever 18 is carried by a fixed pivot 19 located between the ends of the lever, and the rear end 20 of the lever 18 extends into the elevator slot in the path of a web member 21 adjacent the lower end of 25 the elevator.

When a line of matrices has been assembled in the channel 2 of the elevator 1, the elevator is moved vertically, lifting the line of matrices clear of the lug 7. The line of matrices is removed from the elevator by transfer mechanism (not shown) and the elevator is lowered to matrix receiving position. During upward movement of the elevator the web member 21 engages the forward end 20 of the lever 18, rocking the 30 lever about its pivot 19 and depressing the arm 16 of the lever 13, causing the brake 8 to be swung forwardly to release the pressure of the shoes 9 and 10 on the slide bar 6 and permit return movement of the slide bar.

40 The mechanism above described is the conventional line assembly mechanism of a Linotype machine. The present improvement consists of a slide return mechanism operated by the driving mechanism of the machine, provided with 45 controlling means by which its operation is timed with reference to the operation of the elevator and controlling the brake to maintain a substantially uniform pressure on the lines of matrices as they are being assembled.

50 The slide retracting mechanism is in the form of a power driven unit carried by a bracket 22 adapted to be detachably secured to the frame of the machine rearwardly of the slide 6. The bracket 22 has a forked vertical arm 23 which is 55 adapted to straddle a frame bolt 24 by which the bracket may be rigidly secured to a side rail 25 of the machine. The bracket 22 has a horizontal arm 26 adapted to rest upon the top face of the rail 25 and having a bearing portion 27 in which is journaled a tubular shaft 28. The shaft 28 has a driving pulley 29 secured to its inner end by a pin 30 and a clutch disk 31 fixed to its outer end. The pulley 29 engages the drive belt 5 adjacent a driving pulley 32. The bracket 22 also has an arm 33 pivoted thereto which carries a tightener pulley 34 at its outer end. The belt 5 passes under the pulley 29 and over the tightener pulley 34, which may be adjusted vertically to tighten the belt 5 by means 65 of a screw 35 carried by the arm 33 and engageable with the top of the rail 25. The pulley 29, shaft 18, and clutch disk 31 are continuously driven by the belt 5.

A shaft 36 is slidably and rotatably mounted 75 in the tubular shaft 28 and a coil spring 37 is

interposed between the inner end of the shaft 36 and the pin 30. At its outer end the shaft 36 has a threaded portion 38 of reduced diameter upon which is mounted a reel 39 which is clamped on the reduced portion 38 by a nut 40. The reel 39 is normally held in a position clear of the clutch disk 31 by means of the coil spring 37. The clutch disk 31 has a lug 41 on its outer face with which a pin 42 carried by the reel 39 engages when the reel is moved inwardly in opposition to the spring 37 to cause the reel 39 to turn with the shaft 29. The pin 42 is preferably so mounted in the reel 39 that it may move axially if it engages the outer face of the lug 41 upon inward movement of the reel. As herein shown, the pin 42 is disposed parallel to the axis of the reel 39 and has a head 43 which seats in a counterbore in the outer face of the reel. A leaf spring 44 on the outer face of the reel 39 engages the head 43 and yieldably holds 20 the pin in its innermost position.

The reel 39 has a peripheral tapered groove 45 and is connected to the slide 6 by means of a flexible band 46 which extends from the peripheral groove of the reel 39 to the rear end of the slide 6. One end of the band 46 is detachably secured to the slide 6 and the opposite end has a slip connection to the reel. The connection of the band 46 to the reel is through a flexible steel ring 47 which encircles the reel 39 in the groove 30 45 and which is restrained from turning movement on the reel only by its frictional engagement with the walls of the reel groove. The rear end of the band 46, which may be made of leather or other suitable flexible material, is secured to the ring 47. The ring 47 is preferably of a length to encircle the reel 39 and may be secured in place by the band 46. As shown in Figs. 4 and 5, the band 46 has its end secured to an end portion of the ring 47, extends around 40 the pulley, and is secured again to the same end portion of the ring 47. The end of the band 46 may be clamped to an end portion of the ring 47 by a pair of lugs 48 integral with the ring 47, extends around the pulley over the ring 47, and 45 may be secured to the same end portion of the band by a second pair of lugs 49.

The pull exerted by the band 46 on the slide 6 is limited to the sliding friction between the ring 47 and the pulley 39. The return movement of the slide 6 is effected by means of a device connected to the brake 8 and acting to shift the reel 39 into clutching engagement with the disks 31 when the brake 8 is swung forwardly.

55 The reel shifter comprises a lever arm 50 fixed to a vertical pivot pin 51 journaled in a vertical bearing 52 in the bracket 22 and engageable with the reel clamping nut 40. The pin 51 extends below the lower end of the bearing 52 and has a laterally extending arm 53 to which is pivotally connected one end of a pull rod 54 which is pivotally connected at its opposite end to the lower shoe of the brake 8. The rod 54 may be connected to the shoe 10 by means of a screw 55 which may be the screw employed to secure the shoe to the brake arm. The rod 54 is preferably made extensible by a turnbuckle 56.

When the brake 8 is moved forwardly by the lever 13 actuated by the elevator 1 through the lever 18, the reel shifter arm 50 is actuated by the rod 54 to engage the reel 39 with the clutch disk 31 to return the slide 6 to its rearmost position. Upon downward movement of the elevator 1, the lever 18 is released and the spring 37 disengages the reel 39 and shifts the brake 8 to its 70 75 80 85 90 95 98

normal position. The pivot pin 51 has a stop arm 57 which engages with an adjustable stop in the form of a screw 58 in the bracket 22. By adjusting the turnbuckle 56 or the screw 58, the position occupied by the brake 8 during the assembly operation may be adjusted. A stop 59 on the rail 25 limits the rearward movement of the slide 6.

Since no rearward pull is exerted upon the slide bar 6 during the assembling of matrices on the elevator, it is not necessary for the brake to move rearwardly far enough to lock the slide. The brake, however, may be adjusted by means of the stop members 17 and 58 and the turnbuckle 56 to a position such that it will be held by the spring 37 in a position to exert frictional drag upon the slide bar 6 and impose a pressure upon the line of matrices between the lug 7 and star wheel 4 sufficient to insure the proper positioning of the matrices in the elevator channel 2.

The pressure upon the matrices being due to frictional drag, as distinguished from the action of a slide retracting spring, is substantially uniform regardless of the length of the line of matrices assembled on the elevator. By adjustment of the brake the frictional drag may be increased or decreased as desired.

The device of the present invention is adapted to be installed in a type casting machine without any alteration whatever of the mechanism of the machine other than removal of certain parts. The slide returning spring and its connections to the slide bar 6 are removed and the actuating unit shown in Figs. 2 and 3 is mounted on the rail 25 and connected to the slide and brake as shown in Fig. 1.

In the commercial machine the lever 13 is provided with a spring acting thereon in a direction to move the arm 14 forwardly. This spring may be removed upon installation of the device of the present invention, since the rearward movement of the brake 8 is limited by the pull rod 54 and stop arm 57.

The device of the present invention insures a rapid return of the slide bar 6 upon each actuation of the elevator 1 and insures a substantially uniform pressure on the line of matrices during assembly thereof, which pressure may be regulated to insure smooth and certain feed of matrices to the elevator channel. Injury to the mechanism is prevented by the slip connection between the power operated actuator and the slide.

The device of the present invention is simple, compact, and inexpensive, may be applied at small cost to existing type casting machines, and contributes materially to the efficiency of operation of the assembling mechanism.

What I claim is:

1. In combination with the assembling elevator of a type casting machine, the mechanism for delivering matrices to the elevator and the assembler slide which is moved by the matrices as they are fed to the elevator, a slide retracting device comprising a power driven member normally disconnected from the slide, and means controlled by the elevator for connecting and disconnecting said power driven member and slide.

2. In combination with the assembling elevator of a type casting machine, the mechanism for delivering matrices to the elevator and the assembler slide which is moved by the matrices as they are fed to the elevator, a slide retracting

device comprising a power driven member normally disconnected from the slide, means for applying a frictional drag to said slide during the feeding of matrices to the elevator, and means controlled by the elevator for connecting and disconnecting said power driven member and slide. 5

3. In combination with the assembling elevator of a type casting machine, the mechanism for delivering matrices to the elevator and the assembler slide which is moved by the matrices as they are fed to the elevator, a continuously driven shaft, a reel, a band wound on said reel and connected to said slide, a clutch for connecting said reel to said shaft, and means controlled by the elevator for actuating said clutch. 15

4. In combination with the assembling elevator of a type casting machine, the mechanism for delivering matrices to the elevator and the assembler slide which is moved by the matrices as they are fed to the elevator, a slide retracting device comprising a power driven member normally disconnected from the slide, a brake engageable with said slide, means for normally holding said brake in engagement with said slide, and means controlled by said elevator for simultaneously moving said brake to releasing position and connecting said power driven member to the slide. 20

5. In combination with the assembling elevator, matrix feed mechanism and assembler slide 30 of a type casting machine, a continuously driven shaft, a clutch member carried by the shaft, a reel coaxial with said shaft and mounted for movement axially into engagement with said clutch member, a spring acting on said reel and normally holding the reel out of engagement with the clutch, a band wound on the reel and having a slip connection with the reel, said band being connected to said slide, and means controlled by the elevator for shifting the reel into engagement with said clutch member. 35

6. In combination with the assembling elevator, matrix feed mechanism and assembler slide of a type casting machine, a continuously driven shaft, a clutch member carried by the shaft, a reel coaxial with said shaft and mounted for movement axially into engagement with said clutch member, a spring acting on said reel and normally holding the reel out of engagement with the clutch, a band wound on the reel and having a slip connection with the reel, said band being connected to said slide, a brake engageable with the slide, a shifter engageable with said reel to move the same in opposition to said spring, a connection between said brake and shifter for holding said brake in slide engaging position while the reel is disengaged from the clutch, and means controlled by the elevator and acting on said brake to simultaneously move said brake to releasing position and said reel into engagement 60 with said clutch member. 50

7. In combination with the assembling elevator, matrix feed mechanism and assembler slide of a type casting machine, a continuously driven shaft, a reel, a clutch for connecting the reel to the shaft, a flexible metal ring frictionally engaging the periphery of said reel and circumferentially slidable thereon, a band attached to said ring, wound thereon and attached to said slide, and means controlled by the elevator for actuating said clutch. 65 70

GEORGE PANKUCH.
